UNITED STATES PATENT OFFICE.

OTTO F. KRITZNER, OF NILES, MICHIGAN.

SANITARY DRINKING-FOUNTAIN AND FAUCET.

1,161,054.

Specification of Letters Patent. Patented Nov. 23, 1915.

Application filed July 10, 1912. Serial No. 708,671.

To all whom it may concern:

Be it known that I, OTTO F. KRITZNER, a citizen of the United States, residing at Niles, in the county of Berrien and State 5 of Michigan, have invented new and useful Improvements in Sanitary Drinking-Fountains and Faucets, of which the following is a specification.

This invention relates to the class of faucets and pertains especially to a combination sanitary drinking fountain and faucet.

An object of my invention is to provide a faucet the handle of which may be turned in one direction for operating a sanitary drinking fountain and in the opposite direction 15 for operating an ordinary faucet.

Another object of my invention is to provide a communication between the over flow cup of the drinking fountain and the faucet.

20 A further object of the invention is to provide a set screw for controlling the flow of water into the fountain without affecting in any way the flow of water from the faucet should the handle be turned.

25 With the foregoing and other objects in view, my invention consists in such details of construction and arrangement of parts as will be hereinafter fully described and pointed out in the appended claim.

30 In describing my invention in detail reference will be had to the accompanying drawings wherein like characters denote like or corresponding parts throughout the several views and in which,

35 Figure 1 is a longitudinal section of the combination faucet and fountain, and Fig. 2 is a detail perspective view showing the means for controlling the flow of water into the fountain. Fig. 3 is a section on the line 40 3-3 of Fig. 1.

In the drawings the numeral 1 designates the body of the invention, having the unusual water supply passage way 2. Within the body 1 and in communication with the 45 passage way 2 is a tubular shell valve 3, having an opening 4 near the front end thereof. This valve 3 is held in an enlarged passage-way in alinement with the passage-way 2 and against shoulders 5 by means of a spring 6, one end of which presses against a cap 7

50 6, one end of which presses against a cap 7 removably secured to the body by screw-threads, as shown to cover the chamber 8 formed to allow the said spring enough space in which to operate. The said spring 55 6 is held in its proper position by means of the handle stem 9 which is secured to the

valve 3 for turning it. By turning the valve 3 until the hole 4 is at the top of the valve the water is allowed to flow out through the hole and into the pipe 10 screwed to a neck 60 11 on the body 1. By turning the valve 3 in the opposite direction until the hole 4 is at the bottom thereof, the water is allowed to enter the faucet nozzle 12. When the valve is in such a position as shown in Fig. 65 1 of the drawings or the hole 4 is at the side thereof the water supply is entirely cut off by means of the valve fitting snugly within the valve seat with the hole 4 closed by the peripheral wall defining the seat, thereby 70 preventing the water from leaving the valve.

When the valve is turned in such a position as to cause the water to flow through the fountain pipe 10, and over the top edge thereof, it falls into the overflow cup 13 having an outlet 14 for permitting the water to 75 pass into the nozzle 12. The fountain pipe and overflow cup are removably fastened to the body by screw-threads as shown. As a means to prevent the pressure of water flowing into the fountain pipe 10 from being too strong I provide a set screw 15, adapted to be so adjusted as to cause the end thereof to come into engagement with a lug 16 on the valve 3. By setting the screw at any desired 80 distance it will be seen that the valve may be turned for using the fountain until the end of the screw comes in contact with the lug thereby preventing further turning of the valve and in this way only allowing a 85 part of the outlet opening 4 to permit the flow of water therefrom.

It will be seen that this combination faucet and drinking fountain has many novel features and advantages as it permits, by 90 simply turning the handles in one direction, a sanitary means for everyone to drink and also allow those desiring a cup or glass from which to drink to readily fill same by turning the handle in the other direction.

I desire it to be understood that I may make slight changes in the combination and arrangement of parts, provided such changes fall within the scope of the subjoined claim.

Having thus fully described my invention what I claim as new and desire to secure by Letters Patent is:—

In a combined sanitary drinking fountain and faucet, a body portion provided with 110 a supply passage way and an enlarged passage way communicating and in alinement

100

105

110

therewith, a shell valve rotatably mounted in said enlarged passage way and open to said first mentioned passage way, said valve extending at one end without the said passage way, means to yieldingly maintain said valve in engagement with an annular shoulder formed by the enlargement of said passage way, said body portion being provided with opposed outlet passage ways communicating respectively with the fountain and

with the faucet, a lug formed upon the extended portion of the shell, and lug-engaging means penetrating the body portion and adjustable from a point exteriorly of said body to limit movement of the valve, substantially as described.

OTTO F. KRITZNER.
